(57) **CLAIM**

The ornamental design for a motor housing for hair straightening apparatus, as shown and described.

DESCRIPTION

FIG. 1 is an isometric view of an embodiment of a motor housing for hair straightening apparatus showing my new design.

FIG. 2 is a right side elevational view of the motor housing for hair straightening apparatus of FIG. 1.

FIG. 3 is a left side elevational view of the motor housing for hair straightening apparatus of FIG. 1.

FIG. 4 is a front elevational view of the motor housing for hair straightening apparatus of FIG. 1.

FIG. 5 is a rear elevational view of the motor housing for hair straightening apparatus of FIG. 1.

FIG. 6 is a top view of the motor housing for hair straightening apparatus of FIG. 1; and,

FIG. 7 is a bottom view of the motor housing for hair straightening apparatus of FIG. 1.

The broken lines and the unshaded areas within the broken lines illustrate portions of the article and form no part of the claimed design.
